Application March 5, 1930, Serial No. 433,491

3 Claims. (Cl. 60—52)

This invention relates to hydraulic means for imparting a back and forth, intermittent, or reciprocatory motion to a member and to means for effecting such movements at different rates of speed on the working and return strokes of various machines such for example as on the cutting and return strokes of broaching machines.

In many types of machines it is advantageous to use one or more power cylinders for advancing and returning a tool or other instrumentality. A reversible or other type of pump may be provided for supplying pressure fluid to the cylinders and in such cases it is more economical to use a pump having approximately the capacity required to make the working stroke at the desired speed. However when this is done the pump, due to its limited capacity, can only effect the return stroke at approximately the same speed as the working stroke. This procedure results in a considerable loss of time and the desirability of speeding up the return stroke will be apparent.

To remedy this condition without increasing the capacity of the pump over that required for the working stroke, it is proposed to equip the cylinders with pistons having unequal pressure areas on their opposite faces, the greater area being effective on the return stroke, and to provide for by-passing fluid around the piston on the return stroke. The delivery side of the pump is connected to both ends of the cylinder during this return stroke and movement of the piston is produced due to the difference in effective areas on the opposite faces thereof. The piston then acts as a pump to force fluid from one end of the cylinder through the by-pass to the other end of the cylinder. The volume delivered to the cylinder, by the combined flow through the by-pass and from the pump, is so greatly increased that the return stroke is very rapid. In cases where this system has been employed it has been necessary to slow down the return stroke to a speed far below the maximum attainable speed in order to avoid damage to the apparatus or to auxiliaries due to the high pressures and/or velocities resulting from the combined flow and greatly increased volume.

Objects of the present invention are to improve a system of this kind so that the return stroke can be made at greater speeds without damaging or otherwise interfering with the operation of the apparatus or with auxiliaries associated with the apparatus; to provide improved apparatus of this character for operating broaching machines; to provide improved broaching apparatus; to provide improved means for controlling apparatus of this general class; to provide for reducing the number of fittings required for a system of this kind; to provide hydraulic apparatus for these purposes and having an improved circulatory

system; and also to improve the construction and arrangement of parts of apparatus of this character.

In the drawings:

Fig. 1 is a top plan view of a broaching machine; 5

Fig. 2 is also a plan view of a portion of the apparatus shown in Fig. 1, but showing the parts in different relative positions;

Fig. 3 is a longitudinal vertical section of the machine with the pilot withdrawn and the other parts arranged as shown in Fig. 2;

Fig. 4 is a section taken substantially along the line 4-4 of Fig. 1 with the parts arranged as shown in Fig. 2;

Figs. 5, 6, and 7 are transverse vertical sections taken on substantially the same horizontal plane through the body of the control unit to show the parts in different relative positions, Figs. 5 and 6 showing different sections of the choke valve, 20 while the latter is shown in elevation in Fig. 7;

Fig. 8 is a section taken substantially along the line 8-8 of Fig. 5;

Fig. 9 is a section taken along the line 9—9 of Fig. 7; and

Fig. 10 is an elevational view of apparatus for reversing a pump.

The features of this invention, Fig. 1, are illustrated as embodied in a broaching machine of the general type disclosed in my prior Patent No. 1,481,437, issued January 22, 1924, and also in my copending application Serial No. 433,490, filed on even date herewith (issued November 21, 1933, as Pat. No. 1,936,073). This machine comprises a bed 10 which is supported on end pedestals 11 and 12 and is provided with transverse end members 13 and 14 and with longitudinal side members 16 and 17. Intermediate the end members the bed is provided with transverse members 18, 19 and 21, the latter being fitted with an external guide 22 which slidably receives and supports pieces of previously broached stock 23 in which the rear end of the broaching tool 24 is supported. During the broaching stroke a pilot 26, in the member 19, is advanced to the right as shown in Fig. 3, dotted lines, to engage the rear end of the broach 24 to hold the latter stationary. The pilot is connected to the rod 27 of a plunger 28 which is slidable in a cylindrical guide 29, this guide being supported on the transverse member 18. The transverse member 19 carries an external guide 31 which slidably receives the pilot 26 and rod 27 for guiding and supporting the latter during advance and withdrawal of the pilot. A guide plate 30 is mounted on the guide 31 slidably to receive the pilot. The external guide and guide plate function to keep the pilot properly centered with respect to the rear end of the broach. A pitman 32, Fig. 3, is pivotally connected to the plunger 28 and to a crank arm 33, the latter be-

ing fast on a shaft 34 which is supported in bearings 36 (Fig. 1) carried by the frame. The underside of the crank arm 33, as shown in Fig. 3 is in the form of a sector adapted to engage a rack 37 which is slideable longitudinally on the upper exterior surface of an auxiliary cylinder 38. Movement is imparted to the rack 37 by actuating the auxiliary piston 39 in the auxiliary cylinder, the piston rod 41 being connected to a depending lug 42 formed on the end of the rack so as to operate the latter. The auxiliary cylinder is provided with ports 43 and 44 for admitting and discharging pressure fluid.

The stock to be broached, Fig. 3, may be positioned manually but is preferably delivered through a chute 46 to a stock carrier or cross-head 47 when the latter is in its withdrawn position as shown in Fig. 1. The stock may be supported upon the stock carrier by means of brackets or lugs (not shown) in the manner disclosed in my aforementioned prior patent, No. 1,481,437, or as disclosed in my application Serial No. 424,557, filed January 30, 1930 (issued April 25, 1933, as Pat. No. 1,905,506). The cross-head 47, Fig. 1, is mounted for reciprocatory movement in guideways 48 disposed longitudinally along the side members 16 and 17 and motion is imparted to the cross-head, Figs. 1, 2, 4, by the piston rods 49 which are connected to the cross-head and to pistons 51 operating in power cylinders 52. As shown in Figs. 1 to 4 these cylinders are supported in the transverse end member 14 and in the intermediate transverse member 21. The heads of the cylinders, Fig. 4, are connected by tension rods 53 in a manner more fully illustrated in my aforementioned application, Serial No. 433,490 (Patent No. 1,936,073). These cylinders are provided with ports 54 and 56 for admitting and discharging pressure fluid for operating the cross-head.

After the stock has been positioned on the cross-head 47 and before the latter is advanced, the pilot 26 is advanced to the rear end of broach to take the thrust of the cut during movement of the stock over the broach. The front center 57 is advanced to engage the front end of the broach for properly centering and supporting the same. This center, Fig. 3, is carried by a center-retaining member 58 which is cylindrical in form and carries an exterior rib 59 which engages an interior shoulder in the cross-head 47 when the latter is in its withdrawn position as shown in Fig. 1. The center-retaining member 58 is supported for longitudinal movement in a sleeve 61 carried by the end member 13 and held in fixed position therein by a bracket 62 affixed to the end member. The outer end of the center-retaining member 58, Figs. 3, 1, is enlarged in the form of a plunger 63 which is slidably received in the counterbore 64 in the sleeve and this end of the center-retaining member also has a longitudinal bore 66 in which a tubular member 67 is disposed. The outer end of the tube 67 is connected to the bracket 62 and to a pipe connection 68 carried by this bracket. As fluid is admitted through the tube 67 the center-retaining member 58 will be displaced to advance the center. The detailed construction and arrangement of the parts of this front center is further illustrated in my application Serial No. 424,559, filed January 30, 1930 (issued April 25, 1933, as Pat. No. 1,905,508). Pressure fluid for operating the main power cylinders 52 as well as auxiliary cylinder 38, Figs. 3, 4, and the front center 57 is delivered by a constant speed, vari-

able delivery, reversible flow pump 71, Fig. 3, which is driven only in one direction by a suitable motor 72 through a coupling 73, reversal of flow being effected without reversing the direction of rotation of the pump.

The port 56, Fig. 4, in the rod end of each of the main cylinders 52 is connected through the pipe 74, the T 76 and the pipe 77 to one of the ports of the pump 71. The port 54 at the head end of each cylinder 52 is connected through pipe 78 to the other port of the pump and it will be understood that when the pump is operating to deliver fluid through the connections 77, 76 and 74 to the port 56 the piston 51 will be displaced from right to left as shown in Fig. 4 and the cross-head 47 will be moved to advance stock over the broach, this being the working or cutting stroke of the machine. During this stroke fluid will be discharged from the port 54 through the connection 78 to the pump 71. After the completion of this stroke the flow will be reversed so that fluid is delivered through the connection 78 to the head end 54 of the cylinders 52 and fluid will be discharged from the rod end 56 of these cylinders.

It will be observed that the effective area of the rod end of the piston 51 is less than the effective area of the head end of this piston due to the space occupied by the piston rod 49. For good economy it is desirable to keep the capacity of the pump as low as is consistent with good performance and assuming that this pump has sufficient capacity only to advance the cross-head 47 at the desired rate of speed during the working stroke, it will be seen that when the same volume of fluid is delivered to the head end of the cylinder to return the cross-head this volume will only be capable of returning the cross-head at a slower rate of speed than that at which it was advanced. For example if the capacity of the pump were required to advance the cross-head at a speed of approximately 29 feet per minute the pump, due to the larger volume and effective area in the head end of the cylinder, might only be able to return the cross-head at a speed of approximately 25 feet per minute. In order to conveniently and effectively accelerate this return stroke, concentrate the control of the mechanism at a convenient point for operation and repair, and also reduce the amount of piping, connections and valves therefor, a control unit 86, Figs. 5, 6, 7, is interposed between the pump and the power cylinders 52. A connection 82 extends between this control unit and the port 56 at the rod end of the cylinder 52 and a connection 83 also extends between the control unit and the port 54 at the head end of the cylinder 52. As shown in Figs. 5, 6 and 7, this control unit has a delivery passage 84 which affords communication between the connection 83 and the connection 78 of the pump. The connection 74 of the pump also extends to this control unit.

The control unit 86, Figs. 5, 6, comprises a body formed preferably of an intermediate section 87 and end sections 88 and 89, the passage 84 being disposed wholly within the end section 88. The end section 89 has a delivery passage 91 extending therethrough, the ends of the passage being closed by plugs 92, 93 which are threaded therein. A valve ring 94 is threaded into the passage 70 against an interior shoulder 96 and provides a seat for the valve disk 97. A cylindrical wall 98 extends upwardly from the valve disk and is preferably formed integral therewith. A series of longitudinally disposed circumferentially 75

spaced slots 100 are formed in the wall 98 to permit fluid to flow freely through this wall. A valve cage 99 has its cylindrical lower portion threaded into the upper end of the cylindrical wall 98 of the disk 97. Ports 101 are formed in the cylindrical base portion of the valve cage and a tubular section connects the base with a plunger 102 which operates in a dash pot 103 formed in the plug 92. The plunger 102 is provided with ports 104 and with a central bore 106 which slidably receives the stem of the valve 107. The seat for this valve is formed on the upper side of the valve disk 97, the valve being normally held on its seat by a spring 108 which is disposed about the valve stem and seats against the base of the valve cage.

A hollow cylindrical extension 109 depends from the lower side of the valve disk 97 and is reduced at its lower end to fit within a spring 111, the upper end of which seats against the shoulder formed on the cylindrical extension. Ports 112 are formed in the walls of this extension and a port 113 extends longitudinally through the end thereof for affording communication between the valve 107 and the passage 91. An abutment member 114 serves as a seat for the lower end of the spring 111 and has a cylindrical extension 116 disposed within the spring. This abutment member is slidably received in a cylindrical recess 117 formed in the plug 93 and is supported in adjusted positions in this recess by engagement with an adjusting screw 118 threaded through the end of the plug. A suitable number of gaskets 119 are disposed between the head of the screw and the plug for preventing leakage at this point, and it will be understood that upon adjustment of the screw one or more of these gaskets may be added or removed to regulate and control the pressure of the fluid which actuates the front center.

The intermediate section 87 is provided with upper and lower transverse or cross passages 121 and 122. The upper passage has annular recesses 123, 124 formed adjacent the ends thereof and a shuttle valve 126 is disposed in the upper passage for controlling the flow of fluid therethrough. This valve comprises a rod 127 having oppositely disposed valve disks 128, 129 secured thereon by means of nuts 131 which are threaded upon the reduced end portions of the rod and with a plurality of short, radially extended wings 131A positioned thereon substantially 90° apart circumferentially of the rod to position and guide the rod in the passage 121. Seats 132, 133 are formed in the upper passage and are adapted to receive the valve disks 128, 129 respectively. A pipe connection 134 extends into the annular recess 123.

The lower passage 122 is preferably a straight cylindrical passage having annular recesses disposed at the ends thereof to receive the annular seats 136, 137 for a shuttle valve 138. This shuttle valve has a hollow cylindrical body 139 which is formed integral with a transverse end wall 141. This end wall has a central port 142 and a seat 143 for a one way valve 144, this valve being normally held on its seat by a spring 146. An annular member 147 is threaded into the end of the cylindrical body 139 to provide a seat for the spring 146 and this member 147 is also provided with ports 148, 149 to permit fluid to flow freely through this portion of the valve body when the valve 144 is in open position. The end section 89 is provided with upper and lower ports 151, 152, which register with the adjacent ends of the upper and lower passages in the intermediate sec-

tion and afford communication between these passages and the passage 91 in this end section. The end member 88 is also provided with upper and lower ports 153, 154 which register with the adjacent ends of the passages in the intermediate section and afford the communication between these passages and the passage 84 in the section 88. The adjacent surfaces of the end and intermediate sections 87 to 89 have complementary interfitting projections 155 which assist in holding the various passages in alignment. The end and intermediate sections may be secured together in any approved manner, as by means of bolts (not shown).

A choke valve 156 is mounted upon the section 88 and comprises a body portion 157 which may be formed integral with this end section as shown. A pipe connection 158 extends into the body 157 of the choke valve and a right angle passage 159 extends between the connection 158 and a port 161 which affords communication between the passage 84 and the passage 159. This passage, Fig. 9, 159 is enlarged to provide a seat 162 for a one way valve comprising a spherical member 163 which is normally held on its seat by a coil spring 164. This spring is mounted upon a pin 166 carried by a plug 167 which is threaded into the end of the passage 159. Another passage 168 extends from the connection 158 and has a restricted portion 169 for restricting the flow between the port 161 and the connection 158. For convenience of manufacture the passage 168 may be drilled from the side of the body 157 and closed with a plug 171 as shown, the restricted portion being drilled from the passage 84.

The pipe connection 134 on the intermediate section extends to the port 43 at the head end of the auxiliary cylinder 38 (Fig. 3) and the connection 158 on the end section 88 extends to the port 44 at the rod end of the auxiliary cylinder, 40 pressure fluid being supplied through these connections for operating the auxiliary cylinder. Pressure fluid for operating the front center is supplied through the passage 68 which is connected through the T 76 to the connection 77 of 45 the pump.

A fluid reservoir or supply tank 181 (Figs. 1 and 3) is supported upon the transverse members 18 and 19 of the bed plate and a connection 182 extends between the bottom of this supply tank and the upper passage 121 of the intermediate section of the control unit. This passage 121 also has a port 183 and a connection 184 extends between this port and the pump for permitting fluid to flow by gravity from the supply tank to 55 the pump, the supply tank being preferably open to the atmosphere.

Means are also provided for automatically reversing the flow of the pump as the cross-head or stock carrier reaches either end of its stroke. As shown in Figs. 1 and 2 a rod 191 is mounted to slide longitudinally in bearings 192 supported by the frame. Collars 193, 194 are disposed adjacent the ends of the rods and are preferably arranged to be adjustable longitudinally of the rod so that 65 they may be held in various positions. If desired set screws (not shown) may be provided for holding these collars in selected positions. An abutment member 196, Figs. 1, 2, is mounted upon the cross-head 47 in a position alternately to engage 70 one of the collars as the cross-head approaches the ends of its stroke. This engagement causes the rod to move longitudinally in its bearings with the cross-head, the arrangement being such that the rod is moved to the right as shown in 75

Figs. 1, 2 and 3 when the cross-head is moved to its withdrawn position and the rod is also moved to the left as the cross-head finishes its working stroke. A rack 197 (Fig. 10) is formed on the underside of the rod 191 at the end thereof and is engaged by a gear sector 198, the latter being mounted on a shaft 199 which is rotatably supported in the bracket 200 mounted upon the end member 13 of the frame. An arm 201, Fig. 3, is fixedly connected to the shaft 199 and the outer end of this arm has a slot which fits over the rod 202, the arm being held pivotally thereon by round faced nuts 203. In a similar manner the longer arm of a bell-crank 204 is pivotally connected to the lower end of the rod 202 while the shorter arm of this bell-crank is pivotally connected to a rod 206. This bell-crank is mounted to pivot on the pedestal 11. The rod 206 is also pivotally connected to a bell-crank 207 arranged to operate a control plunger 208. It will be understood that when the rod 191 is moved to one of its extreme positions the linkage just described will be effective to reverse the flow in the pump 11 and that when the rod is moved to the other of its extreme positions by engagement with the abutment 196 the sector 198 will be moved in the opposite direction again to reverse the flow.

In the operation of the apparatus with the parts arranged and shown as in Fig. 1 fluid is delivered

30 by the pump through the connections 11 to the T 16 and from this T through the connection 68 to the interior of the center retaining member 58 to advance this member. The rib 59 on the center retaining member however is at this time in engagement with an interior shoulder formed in the cross-head 47 so that the center retaining member 58 can not advance until the cross-head has first moved the stock to be broached on to the end of the broach.

40 Fluid is also delivered by the pump from the connection 11 through the T 16 and the connection 14 to the upper end or chamber 91^a of the passage 91 in the control unit (Fig. 6). When fluid first enters this passage 91^a the valve 97 is

45 held on its seat by the spring 111 and the fluid is diverted through the port 151 to the annular recess or chamber 123 and the pressure of the fluid of this chamber acting against the valve disk 128 of the shuttle valve 126 forces this disk against its seat to close this end of the upper passage 121. Fluid then flows from the chamber 123 through the connection 134 and port 43 to the head end of the auxiliary cylinder 38 and moves the piston 39 from right to left as shown in Fig. 3. This move-

50 ment of the piston 39, due to its connection with the rack 37, serves to rotate the crank arm 33 in a clockwise direction to advance the pilot 26 into engagement with the end of the broach. By adjusting the tension on the spring 111 by means

55 of the screw 118 the pressure in the auxiliary cylinder may be maintained at the proper value to advance the pilot at the desired rate of speed to engage the broach before the cross-head is moved. When the pressure in the upper end of the passage 91^a attains a predetermined value the valve disk 97 will be moved off its seat against the action

60 of the spring 111 and fluid will then flow from the connection 14 through the passages 91^a, 91, and through the lower port 152 into the lower passage 122. On entering this passage the fluid will move

65 the shuttle valve 138 to the left as shown in Fig. 5 to close this end of the passage 122 and fluid will then flow from the passage 122 through connection 82 to the port 56 (Fig. 4) at the rod end of the power cylinder 52, thereby displacing the

piston 51 from right to left and causing the cross-head 47 to advance the stock over the broach for the working stroke. As the cross-head approaches the end of this working stroke the abutment 196 (Fig. 1) will engage the collar 194 and move the rod 191 to reverse the flow through the pump. On this reversal of flow the connection 14 becomes connected to the suction side of the pump and hence will tend to draw fluid out of the passage 91 through ports 112, 113 lifting valve 107 10 and back to the pump through the chamber 91^a and the connection 14. The connection 78 is now connected to the delivery side of the pump and fluid passes through this connection into the passage 84 of the control unit and out through the connection 83 to port 54 at the head end of the cylinder 52. The pressure developed in the passage 84 in the control unit is effective to move the shuttle valve 138 from the position shown in Fig. 5 to the other end of the passage 122 as 20 shown in Fig. 6. Fluid also passes from the passage 84 through the upper port 153 to the annular chamber 124 where it is effective to move the valve disk 129 onto its seat 133, thereby closing this end of the upper passage 121. 25

When the shuttle valve 138 has moved to the position shown in Fig. 6, fluid is permitted to flow from the delivery side of the pump through the connection 78 and the passage 122 to the connection 82 which affords communication with the 30 port 56 at the rod end of the cylinder 52. Pressure fluid is thus delivered to ports at both ends of the main cylinder 52 but as the head end of the piston has a greater effective area than the rod end, the differential pressure will be effective 35 to move the piston from left to right as shown in Fig. 4 to return the cross-head 47 to the position shown in Fig. 1. As this movement of the piston is initiated fluid is forced out of the cylinder through the port 56 and back through the connection 82 into the passage 122 and into the passage 84. It will be seen therefore that during this stroke the rod side of the piston 51 acts as an auxiliary pump to force fluid through the connections just pointed out from one end of the cylinder to the other. At the same time that the piston is functioning in this manner to by-pass fluid from one end of the cylinder to the other, the pump may be operating at capacity to deliver fluid into the passage 84 and into the head end 40 of the cylinder. This arrangement makes available a very large volume of fluid for displacing the piston on its return stroke and it will be apparent that the return stroke may be made very rapidly. 45

50 In such cases it has been found that the cross-head is returned in this manner with greater speed than is required and furthermore the high pressures resulting from this combined flow and increased volume are always far in excess of those to which the auxiliary cylinder and piping should be subjected. The use of such high pressures in this auxiliary cylinder subjects the cylinder, the piston and piping as well as the pilot operating mechanism to unnecessary strain and 55 wear. In many cases where it has been attempted to use such pressures in the auxiliary cylinder the piping has been blown out. Occurrences of this kind are avoided with the present apparatus by the arrangement of the choke valve 70 156. It will be seen that when pressure fluid is admitted to the choke valve 156 (Fig. 9) through the port 161 from the passage 84 the spherical member 163 will be forced on its seat to close the passage 159 and flow to the connection 158 75

leading to the port 44 will be retarded by the restricted passage 169. This assures that fluid at these higher pressures will be delivered through the connection 158 and the port 44 to the rod end 5 of the auxiliary cylinder at a permissible rate and hence the parts operated by this cylinder will function in their intended manner. It will also be seen that when the piston 39 of the auxiliary cylinder is moving from right to left as 10 shown in Fig. 3 the pressure of this fluid will move the spherical member 163 from its seat, Fig. 8, and normal flow will be permitted through the passage 159 and the port 161 to the passage 84 and to the suction side of the pump.

15 In order further to assure that damage will not be caused to the auxiliary cylinder or to the main cylinder 51 or any of the connections or parts operated by these cylinders, the one way relief valve 144 is adapted to open at such pressures as are considered proper. It will be seen from Fig. 7 that when this valve opens fluid may be bled through the shuttle valve 138 into the passage 91 and that the pressures therein will be effective through the ports, 112, 113 to raise the 25 valve 107 from its seat, thereby permitting the fluid to be returned to the suction side of the pump. Should the pressure of the fluid be decreased below the value to which the valve 144 is set to open it will be apparent that this valve 30 will again close.

The function of the port 183 in the shuttle valve 126 is to keep the inlet of the pump submerged through connection 184 (Fig. 3) at all times so that the pump may be supplied with 35 fluid from the supply tank 181. It will be apparent that fluid is permitted to flow by gravity from the supply tank through the connection 182 into the upper passage 121 and out through the port 183 and through the connection 184 to the 40 pump to compensate for leakage and for variation in the quantity of oil required in the system. The shuttle valve 126 is so arranged that it is always open to afford communication with whichever of the passages 74 or 78 happens at that 45 particular time to be connected to the suction side of the pump.

By arranging the various connections and valves in the control unit 86 it is possible greatly to reduce the number of fittings required in a 50 system of this general character and also to centralize the various instrumentalities which control the system. In one particular instance the number of fittings required were reduced by this arrangement from approximately 45 or 50 to 17. 55 It will also be seen that by forming the body of the control unit 86 of separable sections 87, 88 and 89 the various passages may readily be formed by relatively simple manufacturing operations and the various valves and connections 60 may easily be assembled in operative positions and are readily accessible for adjustment.

I claim:

1. The combination with a pressure cylinder having a piston, and a constant speed, reversible 65 flow pump, and a pressure fluid reservoir, of a control unit between and connecting the pump and cylinder and having a body, separate delivery passages from opposite sides of the pump through the body to opposite cylinder ends; an upper cross passage between the delivery 70 passages connected also with the reservoir; a lower cross passage having a shuttle valve and con-

necting the delivery passages, a bleed passage through said shuttle valve; a shuttle valve in the upper cross passage closing it between the delivery passages when the flow is in the first delivery passage, while opening the cross passage between the reservoir and the second delivery passage; the valve in the lower cross passage closing the same between the delivery passages to permit flow from the first delivery passage to the first cylinder end; and upon flow reversal said 10 valve in the upper cross passage closes the connection between the delivery passages and connects the first delivery passage to the reservoir; and the valve in the lower cross passage opens connection between the second delivery passage 15 and the first end of the cylinder, which flow is, as well, to the cylinder end opposite to said first end; the bleed passage in the lower cross passage opening when the flow in this reverse direction attains predetermined pressure to permit 20 flow through the bleed passage to the first delivery passage.

2. The combination with a power cylinder and a reversible flow pump for supplying pressure fluid to the cylinder, of a control unit comprising a body, means providing separate passages from opposite sides of the pump through said body to opposite ends of the cylinder, said body having a passage means connecting said separate passages, a shuttle valve for controlling the flow 30 through said passage means for closing one of said separate passages between the pump and the passage means, and pressure-responsive means carried by the shuttle valve for bleeding fluid from the passage means to said separate passage. 35

3. A control unit for connection between a reversible flow pump, a fluid reservoir and a power cylinder, said unit comprising a body having delivery passages through it for connection between opposite sides of the pump and opposite ends of the cylinder, and having a supply passage for connection between the fluid reservoir and the pump, an upper cross passage in the body and between the delivery passages constituting said connection, and a shuttle valve in said cross passage operable by the fluid pressure in one of the delivery passages to close said passage to the reservoir; and a lower cross passage between said delivery passages with a shuttle valve therein operable to permit pressure fluid flow from one of 50 said delivery passages to one end of the cylinder and also, on reversal, flow from the other delivery passages to both ends of the cylinder simultaneously, and subsequently flow from one cylinder end through said cross passage and through 55 said delivery passage to the opposite cylinder end; said body having auxiliary passages leading from each of the delivery passages for connection to the opposite ends of an auxiliary fluid cylinder, one of said auxiliary passages comprising 60 a plurality of ducts of different sizes, pressure responsive means for normally closing the larger duct, thus restricting the flow through the smaller duct, and to the auxiliary fluid cylinder, the pressure responsive means being operable to 65 provide for normal flow from the auxiliary fluid cylinder; and means for closing one of the delivery passages until the pressure in the auxiliary passage associated therewith attains a predetermined value. 70
